UNITED STATES PATENT OFFICE.

ANDREW A. MATHESON, OF DENVER, COLORADO.

RAILWAY-BRIDGE SIGNAL.

Application filed August 15, 1925. Serial No. 50,385.

To all whom it may concern:

Be it known that I, ANDREW A. MATHESON, a citizen of the United States, residing at the city and county of Denver and State of Colorado, have invented certain new and useful Improvements in Railway-Bridge Signals; and I do declare the following to be a full, clear, and exact description of the invention, such as will enable others skilled in the art to which it appertains to make and use the same, reference being had to the accompanying drawings, and to the characters of reference marked thereon, which form a part of this application.

This invention relates to improvements in signals for railway bridges.

Our railways employ in their construction a large number of bridges. Some of these span large rivers such as the Mississippi and the Ohio, and some conduct the railway across dry ditches that carry water only after a storm or during the periods of melting snow, while other bridges cross streams of intermediate sizes. It frequently happens that the dry ditches and small streams become raging torrents as the result of a cloudburst or heavy rain, with the result that the bridges become undermined and weakened to such an extent that they collapse from the weight of a locomotive or railway train. Serious and fatal wrecks have occurred from this cause.

It is the object of this invention to provide a semaphore signal at the approaches to a bridge and provide means for automatically operating the semaphore at times of high water, thereby apprising the engineer of the possibility of danger.

My invention briefly described consists in providing each bridge with two semaphores, one at each approach, and means that will set the signal to "caution" when the water reaches a level that is liable to cause damage; to "danger" if the water exceeds this level, and to "stop" if the water exceeds the second level.

My invention can be most clearly described and will be most readily understood when reference is had to the accompanying drawing in which one embodiment thereof is shown and in which—

Fig. 1 is a plan view of a bridge to which my signal device has been applied.

Fig. 2 is a cross section of the bridge taken on line 2—2, Fig. 1.

Fig. 3 is a view taken along line 3—3 Fig. 1.

Fig. 4 is a view of the upper end of the semaphore, said view being taken looking in the direction of the arrow 4 in Fig. 2. 60

Fig. 5 is a section taken on line 5—5 Fig. 3.

Fig. 6 is a view similar to 3—3 showing a modified form of operating device.

Fig. 7 is a section taken on line 7—7 65 Fig. 6, and

Fig. 8 is a section taken on line 8—8 Fig. 6.

Numerals 1 and 2 represent abutment piers that support the edges of a railway 70 bridge. The bridge has been shown more or less diagrammatically as consisting of two built up I-beam girders 3 and 4 whose ends rest upon the upper surface of the piers and which support the railway ties 5 that 75 in turn support the rails 6. A vertical support 7 which is preferably a concrete pier such as has been illustrated or an iron beam or post may be substituted for the pier. Secured to the side of the pier that faces up 80 stream are three brackets 8 each of which has a cylindrical bearing 9 adapted to support a cylindrical shaft 10 in such a manner that it can be rotated. Secured to the shaft 10 between each pair of adjacent 85 brackets 8 are vanes 11 which are each provided with spaced bearings 12 and 13. The bearings 12 rest on the upper ends of the cylindrical bearings 9. The bearings 9 have shallow notches 14 which are engaged by 90 lugs 15 that project from the lower end of each bearing 12 and which hold the vanes normally in a predetermined position. The bearings 13, with the exception of the one 95 on the uppermost vane, have cams 16 that are adapted to engage the lower end of the pivoted pawl 17 in the manner shown in Fig. 3. Secured to the shaft 10 by means of pins 18 are cylindrical ratchet members 19 that are adapted to be engaged by the 100 pawls 20 (Fig. 5) that are pivoted to the vanes 11 by means of rivets 21.

It will be apparent from an inspection of Figs. 2, 3 and 5 that when the vanes 11 move clockwise (Fig. 5) the pawls 20 will engage with the ratchets 19 and rotate the shaft 10. The vanes are normally held in the position shown in Fig. 1 by means of a lug that engages the depression 14. All of the vanes except the lower one are held against clock- 110

wise rotation by means of pawls 17 in the manner clearly shown in Fig. 3. When the lowermost vane is rotated, as it will be when the water rises sufficiently to exert the requisite force, it will rotate the shaft 10 and at the same time the cam 16 will release one of the dogs or pawls 17 so that the next higher vane will be free to rotate when the water reaches and engages it. The movement of the second vane releases the third vane, etc. It will be apparent that the rotation of each of the vanes rotates the shaft 10 through a corresponding angle and that the shaft makes a total rotation that is equal to the sum of the angular rotations of the several vanes. The upper end of shaft 10 has a drum 22 about which a few turns of the cable 23 are wound. This cable extends to and is connected with a semaphore signal in such a manner that it moves the signal arm as each of the vanes operate. The semaphore is supported on a post 24 and consists of a casing 25 that houses a lamp 26. The housing has a lens 27 through which the light will pass when the lamp is lit. Pivotally secured to the housing 25 is a semaphore arm 28 to one end of which is attached a quadrant 29 that is provided with three colored lenses that have been indicated by numeral 30. A grooved pulley 31 is connected to the other end of the shaft that carries the semaphore arm and to this pulley the cable 23 is connected. When the signal apparatus is unaffected by the water the lens 27 will be covered by a portion of the quadrant in the manner shown in Fig. 2. When the first or lowermost vane 11 is rotated by the water, it rotates the shaft 10, in the manner explained above, and this movement is then transmitted to the semaphore arm 28 by means of the cable 23. The semaphore is then moved to the first or "caution" position. During the first rotation of the pulley 31 an electrical conductor 32 engages the contacts 33 and closes the circuit that controls the lamp 26 thereby lighting the same. When the signal arm is at any of the three positions, one of the lenses 30 is positioned directly in front of the lens 27, so that the engineer can see the signal even when he cannot distinguish the position of the arm 28. The semaphore and lights are intended to be the same as now employed in standard railway signal practice and have therefore been shown only in a diagrammatic way. If the water rises above the lowermost vane 11 and reaches a sufficiently high level to rotate the vane directly above the shaft 10 is again rotated through a given angle and this in turn sets the semaphore to the next or "danger" position. Should the water reach the third and uppermost vane the signal will be moved to "stop" position. As it is necessary to have a signal at each end of the bridge another cable indicated by numeral 34 is wound

about the shaft 10 at 35 and transmits the movement to the shaft 36 that is pivotally mounted in the bracket 37 secured to the down stream side of the bridge. From the upper end of shaft 36 a cable 38 extends to and is operatively associated with a signal device such as the one just described. These signals are operated in unison so that the same signal is displayed at each end of the bridge. 75

In Figs. 6, 7 and 8 I have shown a slightly modified construction of the operating means, which, however, is merely the equivalent of the one described above. Instead of a single vertical shaft 10 I have provided three short shafts 39, 40 and 41, that are rotatably secured to the pier 7 by means of brackets 42. These shafts are connected by sprocket chains 43 and 44 in such a manner that they all rotate in unison. Shaft 41 has two drums 45 and 46, about which the cables 23 and 34 are wound. When shaft 41 is rotated the semaphores will be rotated in the same manner as when the shaft 10 is rotated. To each of these horizontal shafts I attach a vane 11^a that is free to rotate about the shaft in one direction but which is provided with a pawl 47 that engages the ratchet 48 on the shafts and rotates the shafts when the vane moves in the other direction. A lug 49 is secured to the pier 7 near each shaft and each vane has an arm 50 rigidly secured to it in such a manner that it will be engaged by the lug 49 after the vane has been rotated through a certain angle and thereby prevent the vane from oscillating after it has been first operated. When the water level reaches the lowermost vane it will cause it to swing thereby rotating the shafts and moving the signals to "caution." The arm 50 will prevent the vane from returning. When the water level reaches the second vane this will rotate and move the signal to "danger" position and if the water reaches the uppermost vane the signal will be moved to "stop" position. 95 100 105 110

Having now described my invention, what I claim as new is:

1. In a railway bridge signal, in combination, a semaphore located at an approach to the bridge and means for moving said semaphore to different signaling positions as the water rises above predetermined levels. 115

2. In a railway bridge signal, in combination, a semaphore located at an approach to the bridge, means located underneath the bridge for affecting the semaphore when the water rises above predetermined levels, said means comprising vanes mounted so as to be adapted to rotate about a pivot and means for changing the setting of the semaphore whenever one of the vanes is rotated. 120 125

3. In a railway bridge signal, in combination, a semaphore located at the approach 130

to said bridge, said semaphore having an inoperative or "safe" position and a plurality of operative positions which may correspond to "caution," "danger" and "stop"; means 5 located beneath the bridge and at different levels for moving said semaphore to successive operative positions as the water level rises, said means comprising vanes supported by means that permit them to move 10 about a pivot when they come into contact with running water.

4. A device for operating a signal for the purpose of indicating the approximate maximum level of water in a flowing stream 15 which consists in a combination comprising a plurality of vanes mounted so as to be movable about pivots, each of said vanes being located at a different level whereby each of said vanes causes the rotation of a 20 shaft as it moves in one direction and means connecting said shaft to a semaphore so that the latter is moved when the shaft rotates.

5. A bridge signal operating device comprising, in combination, a plurality of pivot- 25 ally mounted vanes located at different levels

above the bed of a stream, so that they will successively come into contact with the water as its level rises, a shaft mounted for rotation, means operatively connecting each vane to said shaft so that the vanes will rotate 30 the shaft when they move in one direction, and means connecting said shaft with a signal so that the latter will be moved when the shaft rotates.

6. A bridge signal operating device comprising in combination a plurality of pivotally mounted vanes located at different levels above the bed of a stream, so that they will successively come into contact with the water as its level rises, a shaft mounted for 40 rotation, means comprising a pawl and ratchet device for operatively connecting each vane to the shaft so that it will rotate the shaft when it moves in one direction, and means for connecting said shaft to a signal 45 so that the signal will be moved when the shaft is rotated.

In testimony whereof I affix my signature.

ANDREW A. MATHESON.
